UNITED STATES PATENT OFFICE

ANDREAS DOMASCHKO, DECEASED, LATE OF VIENNA, AUSTRIA, BY ANNA DOMASCHKO,
ADMINISTRATRIX, OF VIENNA, AUSTRIA, ASSIGNOR OF ONE-HALF TO CARL BAETH,
OF VIENNA, AUSTRIA

IMPULSE EMITTER

Application filed April 30, 1927, Serial No. 187,984, and in Austria May 6, 1926.

This invention relates to impulse emitters and particularly to those employed in automatic telephone exchanges.

The effect to be realized by means of such impulse emitters consists in alternately sending electric impulses into the two branches of the line, which branches might constitute parts of separate circuits including besides other connections also the earth, in such manner, that the series of the impulses emitted into the one of these branches can be varied, this particular latter branch being herein-after called the *a*-wire, whilst the other branch is called the *b*-wire.

The main object of the present invention is an arrangement owing to which, after certain members determining the number of impulses to be sent consequently as one series into the *a*-wire have been set accordingly and after the spring driving the apparatus has been wound up, all the impulses are automatically sent into the *b*-wire as well as into the *a*-wire so, that the *b*-impulses will directly follow the *a*-impulses for the purpose of reducing the time necessary for establishing a connection to the minimum possible. According to the invention this is realized by the feature, that for the emission of the *b*-impulses as well as for that of the *a*-impulses separate gears are provided, which are mutually locking and liberating one another.

Another object of the invention is an arrangement for rendering inoperative one or more series of impulses, whereby one and the same impulse emitter may be used for telephone exchanges with a large or small number of subscribers.

Another object of the present invention is to keep the gears locked until a first group selector has been found, so that wrong connections in installations with a relatively small number of first group selectors are avoided.

Some more characteristic features of the invention will be explained with reference to the drawing in which a construction according to the invention is illustrated by way of example.

Fig. 1 shows the plan view of the setting mechanism and Fig. 2 its back view, Fig. 3 is a plan view of the lever mechanism stopping

and starting the gears, Fig. 4 an elevation, partly sectional, of the mechanism for starting the impulse emitter, Fig. 5 shows the two gears for the impulses in the *a*-wire and in the *b*-wire, Fig. 6 a mechanism, which is used, when the number of the existing first group selectors is relatively small and Fig. 7 the apparatus in its entirety at an enlarged scale, parts being broken off.

The mechanism for setting the number to be called up (Figs. 1 and 2) is mounted on a disc 1 which, in the construction illustrated, constitutes the front wall of the casing and is rotated by the wheel 2 of the gear for the impulses in the *b*-wire through the gear wheel 3 connected to the disc. The gear wheels 2 and 3 are of the same diameter, so that the disc 1 makes one complete revolution during the running of the gear to the end of its movement, as will be seen from the following description. To the disc 1 is rigidly secured a second disc 4 which is provided near its circumference with pins 5, 5a, 5b, the number of which is equal to the number of places of the highest call number. In the construction illustrated, the number of subscribers is assumed to be one million, and therefore six pins are provided. The pins 5a and 5b are at a greater distance apart than the other pins, the distance apart of which is the same. Between the disc 1 and the disc 4 are arranged cam discs 6 which for the purpose of setting can be turned by means of the buttons 8. On the circumference of each cam disc 6 ten steps of equal form and height are provided, corresponding to the number 0 to 9. The cam discs 6 are held in the position adjusted by means of a locking device 9, 10.

To the spindles 7 of the cam discs are secured number discs 11 which show the setting of the cam discs through the windows 12.

The gears which produce the impulses in the *a*- and *b*-wire are locked and released by the pins 5. The number of impulses emitted into the *a*-wire is dependent upon the position of the cam discs 6.

The producing gear for the impulses in the *a*-wire (Figures 3 and 5) comprises the toothed wheel 12 secured to the spindle of the spring casing, as well as the toothed wheels 13,

13, 14, 15, 16, 17, 18, 19 and the blade 20 acting as speed regulator. The gear is normally locked by a wing or blade 21 which is secured to the spindle 15a of the toothed wheel 15 and prevented from rotating by a projection 22 of a lever 23. The lever 23 is rotatable about a spindle 24 and controlled by a spring 25 which tends to turn it downwards. This rotation is prevented by a locking hook 28 which, under the action of pressure of a spring 29, engages with the teeth 27 of the lever 23. Two teeth 37 on the spindle 15a of the toothed wheel 15 co-operate with the teeth 27 and engage with them only when the gear begins to run. The pawl 28 rests on a side-wise bent extension 26a of a lever 26, mounted on the same spindle as a lever arm 32, the bent end 33 of which is situated in the path of the pins 5. The lever 26 has a recess 26b, with which engages a lever 30, the free end of which comes, when the lever is turned, into the path of the blade 20, thus stopping the latter. To the spindle 24 of the lever 23 is secured an arm 34, the bent end 34a of which, when the lever is turned, strikes against one of the steps or teeth 39 of the cam disc 6.

The contact gear of the *a*-wire is constituted by a spring controlled lever arm 35, and by pins 36 on the toothed wheel 14 (Fig. 5). During the rotation of the toothed wheel 14, the arm 35 is moved like a pawl sliding over a ratchet wheel, and slides during that movement over the pins 36. Each touch causes an impulse to be emitted into the *a*-wire.

When the disc 4 is rotated in the direction shown by the arrow (Fig. 3) one pin 5 is brought into engagement with the bent end 33 of the lever arm 32, and raises the same. In this way, the pawl 26 and by the extension 26a also the locking hook 28 is turned. The toothed part 27 and consequently the lever 23, is now free and under the action of the spring 25 swings downwards, so that the blade 21 is disengaged from the projection 22. The down movement of the lever 23 is limited by the arm 34, the end 34a of which comes to rest on one of the steps 39 of the cam disc 6. The turning of the pawl 26 results in the lever 30, engaging by means of its extension 30a with the recess 26b being also turned, so that its pointed end is brought into the path of movement of the blade 20, owing to which the running of the gear is prevented in spite of the fact that there is no locking at 21, 22. As soon as the lever 32 drops off the pin 5, the lever 30 returns to its initial position, whereby the locking of the blade 20 is cancelled.

The gear can now run, the pins 36 passing in front of the lever arm 35, owing to which impulses are produced in the *a*-wire. The running of the *a*-gear also causes the toothed member 23 to be turned back, as the teeth 27 of the latter are engaging with the two

teeth 37 on the shaft of the blade 21. The number of impulses depends on the position of the cam disc 6, as the latter determines the extent of deflection of the toothed member 27. The greater the distance of the respective step or cam 39 chosen by the setting from the centre of the disc 4, the smaller the angle to which the member 27 can be turned from the initial position when the extension 34a is resting on the step 39 of the cam disc 6, to the final or end position determined by the engagement of the blade 21 with the projection 22, and accordingly the smaller will be the number of revolutions which the spindle of the toothed wheel 15 or of the teeth 37 can make, and consequently also the spindle of the wheel 14 carrying the contact pins.

The gear for the impulses in the *b*-wire (Figure 5) is driven by a toothed wheel 40 on the spring casing, which transmits the movement through the toothed wheels 41—47 to the blade 50 acting as speed regulator. The locking of the wing or blade 50 is effected by means of an arm 52 (Fig. 3) of a lever rotatable at 54, the other arm 53 of which, in the position of the parts shown in Figure 3, by means of an extension 55 rests on the lever 23, whereby the arm 52 is held out of engagement with the blade 50 in opposition to the action of a spring. The gear can thus run and produces impulses in the *b*-wire, owing to an arm 51 secured in an insulated manner to the framework and connected to the *b*-wire, engaging with pins 57 of the wheel 42 (Fig. 5). As after the impulses have been sent into the *a*-wire, only one single impulse is sent into the *b*-wire, the driving gear must be stopped again after each contact. This is done by means of one of the pins 5 on the disc 1, which pin turns the lever 32. In this way, as will have been seen from the preceding description, the lever 23 is also turned, and therefore the engagement between 55 and 23 is ceased. The arm 52 can now swing and is by the action of the spring controlling it brought into the path of movement of the blade 50, which is locked thereby, owing to which the gear for sending impulses to the *b*-wire is prevented from running. The sliding off of the lever 32 from the pin 5 further results in the locking 30, 20 being cancelled, so that the *a*-gear begins to run at the moment of stoppage of the *b*-gear. When after the run of the *a*-gear has been completed, the lever 23 is brought back again to an initial position, it engages with the extension 55, owing to which the locking at 52, 50 is undone. The *b*-gear will then run until the lever 32 slides off from the next pin 5. The two gears therefore release and lock each other. Whilst however, the time of running of the *b*-gear is constant, as it is operative during the movement of the disc 1 to the angle which corresponds to the dis-

tance between two pins 5, the time of running of the *a*-gear varies with the position of the cam discs 6.

At each operation of the impulse emitter, 5 the disc 4 makes one complete revolution. Accordingly, the toothed wheel 2 co-operating with the toothed wheel 3 of the same size, must only rotate once, which is ensured in the following manner. On the spindle of the 10 toothed wheel 2 is mounted a disc 58, with the recess 59 of which engages a lever 60. On one face of the lever is provided a projection 61 which prevents the *b* gear from running, as it is situated in the path of movement 15 of a pin 62 on the wheel 44 and therefore locks the gear. The lever 60 is mounted on an adjustable spindle 64 which is held in position by a spring 63. The end of the spindle has an arm 65 (Figs. 3 and 4) which rests on 20 a disc shaped enlargement 70a of a sleeve 70. This enlarged part 70a rests on a ratchet wheel 66, provided with a downward enlarging slot 67 with which engages a pin 68 of the spindle 69. The spindle 69 is mounted in the 25 sleeve 70, which is supported by a fixed piece of tube 71. A spring 72 rests on a flange 73 of the spindle 69, and also on the sleeve 70, holds the pin 68 in engagement with the slot 67 of the ratchet wheel 66. The rotation of the latter and of the spindle 69 to which is secured 30 the gear spring, is effected by the swinging movement of a lever 74 to be moved to and fro by hand and provided with a pawl 75, which under the action of a spring 77 engages 35 with said ratchet wheel 66.

The gear spring mounted on the shaft 69 is set by actuating the lever 74 until the circumferential force is so great that the ratchet wheel 66 overcomes the tension of the spring 40 72 and is lifted owing to the co-operation of the cam slots 67 with the pin 68. With the ratchet wheel 66 is also moved the arm 65 resting on the enlarged part 70a and the lever 60, the projection 61 of which releases the pin 45 62, so that the *b*-gear is free to run. When after making one revolution the pin 62 again reaches the position of the projection 61, it is no longer prevented by the latter from turning, as the lever 60 has passed in the mean- 50 time from the recess 59 to the plain circumference of the disc 58. Only when this disc has made a complete revolution, the lever 60 engages again with the recess 59 and locks the *b*-gear which is then released again only by 55 a renewed operation of the hand lever 74.

When the lever 60 moves to the plain circumference of the disc 58, simultaneously also the arm 65 is turned, as it is mounted on the same spindle 64. Thereby it encounters 60 a pin 78 on the pawl 75, which thereby is turned and thrown out of engagement with the ratchet wheel 66. Swinging the hand-lever 74 is therefore inoperative during the running of the gear.

65 For pursuing the action of the apparatus

it may be assumed that the connection with the subscriber's station No. 795,316 ought to be effected. For this purpose the cam discs 6 are by means of the buttons 8 turned so that the number discs 10 show the said desired number. Now the lever 74 is actuated and thereby the spring mounted on the shaft 69 is wound up. When the tension of the spring will have reached a certain value, the lever 65 and the lever 60 connected to it are 70 lifted, so that the projection 61 and the pin 62 on the wheel 42 will disengage. The *b*-gear is now free to turn, as the lever 52 is out of the path of movement of the blade 50, the *a*-gear being meanwhile prevented 75 from running by the projection 22 of the lever 23.

Owing to the run of the *b*-gear the arm 51 engages with a pin 57 of the wheel 42 and one impulse is sent into the *b*-wire. 80 By the *b*-gear also the disc 4 is turned, the first pin 5a of which after emission of the first *b*-impulse will act on the lever 33. The turning of the lever 33 causes also the lever 28 to turn, which sets free the toothed lever 23, so that the latter will swing downward until the extension 34a will strike against the disc 6. During the swinging movement of the lever 23 the two gears are locked, viz. 85 the blade 50 of the *b*-gear by the arm 52 and the blade 20 of the *a*-gear by the lever 30. But the latter locking is undone again as soon as the lever 32 drops off the pin 5. The *a*-gear can now run, so that the contact lever 90 35 with engagement with the pins 36 will send impulses into the *a*-wire. During this run of the *a*-gear the lever 23 will, owing to the engagement of the teeth 37 of the shaft 15 with the teeth 27, be moved back again into its initial position, which is attained, when 95 the blade 21 will be again in engagement with the projection 22. The *a*-gear is thereby locked, whilst the *b*-gear is free to run, as the lever 23 has turned the arm 52, which thus is put out of the path of movement of the blade 50. The *b*-gear can now run until 100 the next pin 5 will engage with the lever 32, whereby again one single impulse is sent into the *b*-wire. The turning of the lever 32 causes the *a*-gear to run again. The number of impulses emitted in the *a*-wire depends 105 upon the position of the cam discs 6, which is such, that after the first *b*-impulse 7 *a*-impulses are emitted, after the second 9, after the third 5, after the fourth 3, after the 110 fifth 1 and after the sixth 6.

When all the impulses are emitted into the *a*-wire as well as into the *b*-wire, the wheel 58 with the recess 59 will have completed one revolution. The lever 60, which by the circumference of the disc 58 had been kept in its lifted position, now engages with the recess 59, whereby the extension 61 is brought to engage with the pin 62 and the *b*-gear is locked. For setting the apparatus to work 115 120 125 130

again the lever 74 has to be actuated again.

- The impulse emitter is further provided with a device by which one and the same apparatus for installations of different size may be used. It comprises a lever which is built up of two parts 81a, 81b insulated by an intermediate piece 82 (Fig. 6) and is controlled by the pressure of a spring 83. The half 81a of the lever is connected to earth.
- 10 One end of the lever is formed into a nose 84 which co-operates with a disc 85a, 85b whilst the other end is intended in one position (that shown in the drawing) to connect electrically two contacts 86 and 87 secured to and insulated from the framework, which contacts do not touch each other after the lever has been turned. Of the said contacts, the contact 86 is connected to the α -wire leading to the telephone instrument, and the contact 20 87 to the α -wire leading to the exchange. The disc 85a, 85b is mounted on the same spindle as the disc 58, and like the latter, makes one complete revolution at each operation of the impulse emitter. It is built up of two parts 25 85a and 85b which can be turned separately and fixed to one another. Each part is provided on the circumference with a recess, the depth of which is such that the nose 84 does not touch the disc. During the rotation of 30 the disc 85a, 85b in the direction indicated by the arrow, the nose 84 of the lever 81 is brought into engagement with the face 89 of the recess of the disc 85a, and is raised by the same to the circumference of the discs, owing 35 to which an electric connection is made between the lever part 81a and the disc 85. The connection is broken again as soon as the nose 84 slides off from the edge 90 of the recess of the disc 85b. By adjusting the 40 disc 85a, the nose 84 may be made to contact with the disc circumference, and the electric connection to the lever 81a effected at an earlier or later moment.
- For explaining the operation, let it be assumed that the impulse sender which is arranged for use in a telephone installation with several hundred thousands of subscribers is to be used in an installation with only several tens of thousands of subscribers. In accordance with the smaller number of subscribers, the disc 85a is set in such a manner that the nose 84 of the lever 81 engages with the circumference of the discs 85a and 85b only when the disc 1 has made one sixth of a complete revolution. The gear spring is now wound up by means of the lever 74, until the locking of the b -gear at 61, 62 is cancelled by the movement of the lever 60. As soon as the gear begins to run, the disc 1 is also rotated.
- 50 Owing to the running of the b -gear, a contact is produced between 51, 57 which however remains inoperative, as the earth connection has not yet been made. After the lever 32 has dropped off from the first pin 5a, the gear for 55 the b -impulses is locked by the arm 52. The

gear for the impulses in the a -wire now runs to the extent determined by the position of the corresponding cam disc 6, until the blade 21 comes in engagement with the projection 22, but these impulses also remain inoperative, as the first contact of the b -wire has not taken place. The nose 84 now comes on the circumference of the disc 85a, 85b and the lever 81a, 81b is turned, owing to which the electric connection between 86 and 87 is broken and the disc 85a, 85b connected to earth by the lever arm 81a. The next impulse in the b -wire will therefore be operative. Owing to the sliding off of the lever 32 from the second pin 5, the gear for the b -impulses is locked again. Impulses follow in the a -wire, the number of which is determined by the position of the second cam disc. The same thing is repeated six times, whereupon the lever 60 again engages with the recess 59 of the disc 58 and locks the b -gear at 61, 62, which is released again only by a fresh operation of the lever 74.

If the impulse emitter is to be used for installations for several hundred thousands of subscribers, it is merely necessary to turn the disc 85b so as to ensure that the lever 81 will be raised at the beginning of the run of the gear.

If the installation contains a relatively small number of first group selectors, the use of the device described is liable to lead to the disadvantage that wrong connection might be made owing to the first group selector which at the moment of the arrival of the first impulse of the series is still engaged, but shortly afterwards becomes free and available, being reached not by the first impulse of the a -wire, but only by a later impulse, certain impulses intended for lower place values no longer becoming operative at all. This disadvantage is eliminated by the construction of the device shown in Figure 6, in which the gear remains locked until a free first group selector has been found.

106 is a lever turning on the spindle 100, the end 106a of which lever (Fig. 5) is brought within the path of movement of the blade 47, when the lever is turned. The other end 107 of the lever constitutes an armature acted upon by an electro-magnet 108. 102 is an extension of the lever, which by a spring acting on the lever is pressed against the circumference of the discs 85a, 85b. 104 is a pin on the disc 85a and 105 a spring, connected by means of an electric wire to the winding of the electro-magnet 108, the other end of which winding is connected to the a -wire leading to the exchange.

The end 106a of the lever is, when the b -gear begins to run, situated outside the path of movement of the blade 50. If the disc 85a, 85b has turned so far, that the extension 102 can engage with the recess of the disc, the lever 106 is turned and the blade 50 locked.

But this locking can only take place, when no first group selector is free. If at the moment, in which the extension 102 had the possibility of dropping into the recess of the discs 85a, 85b, a first group selector was free, electric current was supplied from the exchange to the electro-magnet 108, as at this position the pin 104 touches the spring 105. The electro-magnet attracts the armature 107 and thereby moves the lever end 106a out of reach by the blade 50.

Figure 6 shows further a device by means of which a connection between the *a* and *b* wires is established after the run of the gears, 15 in order to break the connection again if the receiver had not been taken off before the gears have ceased to run. This device is constituted by a contact connected to the *b*-wire and made in the form of a key 110, the lateral 20 face 111 of which is provided with an insulating covering. When the lever portion 81b is turned owing to the nose 84 sliding on to the circumference of the disc 85a, 85b, the end of this lever portion slides on the insulated 25 covering 111. During the return movement of the lever 81a, 81b which takes place after the gears have accomplished their run, owing to the projection 84 engaging again with the recess of the disc 85a, 85b, the end of the lever 30 portion 81b comes into contact with the non-insulated lateral face of the key 110, owing to which a connection will be established between the *a* and *b* wires. In order to avoid any disturbance in emitting the impulse by 35 the lifting of the telephone receiver, there is provided in the *a*-wire to the telephone instrument a break or interruption 86, 87 which is short circuited by the lever portion 81b only after all the impulses have been sent. 40 If the receiver had been taken off before, the circuit to the telephone instrument will be interrupted by this break in the *a*-wire.

What is claimed is:

1. An impulse emitter for telephone exchanges adapted to be connected in circuit with two branches of the line including a plurality of separate circuits comprising a contact wheel adapted for emitting impulses into the one branch of the line, a gear driving said contact wheel, an oscillating element for locking the said gear, means for releasing the said locking element, a second contact wheel adapted for emitting impulses into the second branch of the line, a second gear driving this second contact wheel, and means for locking and releasing the second gear.

2. An impulse emitter for telephone exchanges adapted to be connected in circuit with two branches of the line including a plurality of separate circuits comprising a contact wheel adapted for emitting impulses into the one branch of the line, a gear driving said contact wheel, an oscillating element for locking the said gear, means for releasing the 65 said locking element, a second contact wheel

adapted for emitting impulses into the second branch of the line, a second gear driving this second contact wheel, and means for locking and releasing the second gear, which means are connected with the means for locking the first gear whereas the means for releasing the first gear are connected to the second gear. 70

3. An impulse emitter for telephone exchanges adapted to be connected in circuit with two branches of the line including a plurality of separate circuits comprising a contact wheel adapted for emitting impulses into the one branch of the line, a gear driving said contact wheel, an oscillating element for locking the said gear, means for releasing the said locking element, a second contact wheel, a gear for driving this second contact wheel, means for locking and releasing this second gear and a spring drive, the shaft of which 85 is connected to the first gear while its casing is connected to the second gear. 80

4. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, gears for driving said contact wheels alternately and means for locking the second gear after emission of all the impulses. 90

5. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, gears for driving said contact wheels alternately, a lever for locking the second gear after emission of all the impulses, and means for maintaining this lever in the non-operative position 100 during the run. 105

6. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, gears for driving said contact wheels alternately, a lever for locking the second gear after emission of all the impulses, and a disc for maintaining this lever in the non-operative position during the run. 115 120

7. An impulse emitter for telephone exchanges adapted to be connected in circuit with two branches of the line including a plurality of separate circuits comprising a contact wheel adapted for emitting impulses into the one branch of the line, a second contact 125 130

wheel adapted for emitting impulses into the second branch of the line, gears for driving said contact wheels alternately, a lever for locking the second gear after emission of all the impulses, and means for releasing this lever connected to the device for tensioning the spring driving the gears.

8. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, gears for driving said contact wheels alternately, a lever for locking the gear for the second contact wheel after emission of all the impulses, such lever being connected to a slidable coupling element of the device for tensioning the spring driving the gears.

9. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, a first gear and a second gear for driving said contact wheels, a lever for locking the gear driving the second contact wheel, and an electromagnet for controlling the locking lever connected on the one hand to the branch of the line leading to the exchange and on the other to a contact-element on a disc rotated by the second gear.

10. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, a first gear and a second gear driving said contact wheels, a lever for locking the second gear, an electro-magnet for controlling the locking lever, and a disc for locking the locking lever.

11. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, gears for driving said contact wheels, a lever connected to earth and a disc adapted for controlling said lever, which disc is provided with a recess and is rotated by the gear driving the second contact wheel.

12. An impulse emitter for telephone exchanges adapted to be connected in circuit

with two branches of the line including a plurality of separate circuits comprising a contact wheel adapted for emitting impulses into the one branch of the line, a second contact wheel adapted for emitting impulses into the second branch of the line, gears for driving said contact wheels, a lever connected to earth and two discs adapted for controlling said lever, which discs are provided each one with a recess and adjustably connected to one another.

13. An impulse emitter for telephone exchanges adapted to be connected in circuit with two branches of the line including a plurality of separate circuits comprising a contact wheel adapted for emitting impulses into the one branch of the line, a second contact wheel adapted for emitting impulses into the second branch of the line, gears for driving said contact wheels, a lever controlled by a disc of the gear driving the second contact wheel, and adapted to be connected to the one branch of the line receiving its impulses from the first contact wheel, and a key-shaped contact member with one insulated face lying on the path of movement of the said lever.

14. An impulse emitter for telephone exchanges adapted to be connected in circuit with two branches of the line including a plurality of separate circuits comprising a contact wheel adapted to emit impulses into one branch of the line, a gear driving said contact wheel, and an oscillating element for locking and releasing the driving gear, said element being provided with teeth adapted to engage with the teeth of a driving wheel of the said gear.

15. An impulse emitter for telephone exchanges adapted to be connected in circuit with two branches of the line including a plurality of separate circuits comprising a contact wheel adapted to emit impulses into one branch of the line, a gear driving said contact wheel, an oscillating element for locking and releasing the driving gear, said element being provided with teeth adapted to engage with the teeth of a driving wheel of the said gear, and means for locking the oscillating element.

16. An impulse emitter for telephone exchanges adapted to be connected in circuit with two branches of the line including a plurality of separate circuits comprising a contact wheel adapted for emitting impulses into one branch of the line, a gear driving said contact wheel, an oscillating element for locking and releasing the driving gear, said element being provided with teeth adapted to engage with the teeth of a driving wheel of said gear, means for locking the oscillating element, and means for limiting the amplitude of oscillation of said element.

17. An impulse emitter for telephone ex-

changes adapted to be connected in circuit with two branches of the line including a plurality of separate circuits comprising a contact wheel adapted for emitting impulses 5 into one branch of the line, a gear driving said contact wheel, an oscillating element for locking and releasing the driving gear, said element being provided with teeth adapted to engage with the teeth of a driving 10 wheel of said gear, means for locking the oscillating element and discs with tooth-like cams for limiting the amplitude of oscillation of said element.

18. An impulse emitter for telephone exchanges adapted to be connected in circuit with two branches of the line including a plurality of separate circuits comprising a contact wheel adapted to emit impulses into 20 one branch of the line, a gear driving said contact wheel, an oscillating element for locking and releasing the driving gear, said element being provided with teeth adapted to engage with the teeth of a driving wheel 25 of said gear, means for locking the oscillating element and discs with tooth-like cams for limiting the amplitude of oscillation of said element, mounted on an intermittently rotating disc.

19. An impulse emitter for telephone exchanges adapted to be connected in circuit with two branches of the line including a plurality of separate circuits comprising a contact wheel adapted to emit impulses 35 into one branch of the line, a gear driving said contact wheel, an oscillating element for locking and releasing the driving gear, said element being provided with teeth adapted to engage with the teeth of a driving 40 wheel of the said gear, means for locking the oscillating element, discs with tooth-like cams for limiting the amplitude of oscillation of said element mounted on an intermittently rotating disc, and means for setting the cam discs.

20. An impulse emitter for telephone exchanges adapted to be connected in circuit with two branches of the line including a plurality of separate circuits comprising a 50 contact wheel adapted for emitting impulses into one branch of the line, a gear driving said contact wheel, an oscillating element for locking and releasing the driving gear, a lever for locking the oscillating element, and 55 means for releasing the said lever at intervals.

21. An impulse emitter for telephone exchanges adapted to be connected in circuit with two branches of the line including a 60 plurality of separate circuits comprising a contact wheel adapted for emitting impulses into one branch of the line, a gear driving said contact wheel, an oscillating element for locking and releasing the driving gear, 65 a lever for locking the oscillating elements,

and means for releasing the said lever mounted on an intermittently rotating disc.

22. An impulse emitter for telephone exchanges adapted to be connected in circuit with two branches of the line including a 70 plurality of separate circuits comprising a contact wheel adapted for emitting impulses into one branch of the line, a gear driving said contact wheel, an oscillating element for locking and releasing the driving gear, 75 means for locking the oscillating element and a lever adapted for locking and releasing the driving gear, and connected to the said means for locking the oscillating element.

In testimony whereof I have affixed my signature.

ANNA DOMASCHKO,
